UNITED STATES PATENT OFFICE.

CHARLES W. CORNELL, JR., OF SAN FRANCISCO, CALIFORNIA, ASSIGNOR OF ONE-HALF
TO WILLIAM N. McCAW, OF SAN FRANCISCO, CALIFORNIA.

AERONAUTICAL DEVICE.

1,172,198.

Specification of Letters Patent. Patented Feb. 15, 1916.

Application filed August 13, 1914. Serial No. 856,700.

To all whom it may concern:

Be it known that I, CHARLES W. CORNELL, Jr., a citizen of the United States, residing in the city and county of San Francisco, 5 State of California, (whose post-office address is 600 Geary street,) have invented a new and useful Aeronautical Device, of which the following is a specification.

This invention relates more particularly 10 to sailing devices, adapted to glide up and down upon the tethering line of flying kites.

This invention is designed more particularly as an amusement device, but it is also a practical utility for carrying up scientific 15 instruments such as barometers, thermometers, cameras, and scientific instruments for meteorological observations at great heights.

This invention can also be used to carry up bombs, pyrotechnical displays, and other 20 objects to be exploded or dropped from a height.

Among the objects of this invention are to provide an aerial glider adapted to engage a kite line up which it is carried by 25 wind pressure, until it reaches the kite, whereat, the sail or plane will be automatically released, permitting the device to glide down the string.

Other objects and advantages will appear 30 as the description progresses.

In the drawing accompanying and forming part of the present specification, to which like reference characters have been applied, a simple form of putting this invention 35 into practice is shown. I do not wish to be understood as confining this invention to the disclosure made in said drawing and description, as many variations may be introduced, within the spirit of this invention 40 as defined in the claim succeeding the said description.

In the drawings the figure illustrates a perspective view of a glider constructed in accordance with this invention, showing the 45 sail in the ascending position.

In detail, the construction illustrated in the drawings includes the vertical mast 1, having the downward extension 2, provided with a counterbalancing pendulum 3, to 50 maintain the mast substantially perpendicular in operation.

The mast is supported by a runner 4, rigidly attached at 5 to the mast and having the spiral guides 6 at each end adapted to

engage the kite line. The sail 7 is provided 55 with the upper and lower arms 8 and 9, and is secured to the mast at the bottom by the bracket 10 fixed on the mast above and transversed to the runners 4, the opposite ends of the bracket are bent into the loops 60 11-11 encircling the lower cross arm 9 to act as a pivot or hinge upon which the sail swings when released from the perpendicular. The sail is held in the perpendicular position by the latch 12 pivoted at 13 on 65 the top of the mast; the latch has the extension 14 engaging the loop 15 attached to the upper arm 8 of the sail. The latch 12 is held in the operative position by the cord 16, extending from the latch downward under 70 the arm 9 and outward to the end 17 of the trigger 18, pivoted at 19, on the pivot 20, attached to the runner adjacent to the spiral guides 6. The trigger 18 is held in the normal position by the tension of the coil 75 spring 21, attached to the end of the trigger and to the runner at 22, to hold the cord 16 taut.

The invention is operated as follows:— 80 Presuming the kite to be under control at a desirable height. The glider is attached to the kite string by reeving the string into the spiral guide 6—6, the string being taut cannot be dislodged from the guides except by proper manipulation. The sail is 85 latched up in the position shown in Fig. 1, the tension of the spring 21 operating to hold the latch in the position to lock the sail in this position. The pendulum weight holds the mast upright, and the sail at the 90 proper drawing angle to the kite line, omitted from the main drawing to avoid confusion of lines. The glider mounted upon the kite line as described is forced upward upon the line by the same wind pressure that causes the kite to soar. Under this wind pressure the sail carries the glider up the kite line until the extension 23, on the trigger 18, abuts the disk 24, attached to the kite line at any desired point, preferably near the kite. The abutment of the trigger against the disk 24, swings the trigger on its pivotal center 19, against the tension of the spring 21, which causes the cord 16 to slacken, releasing the latch 14 from 95 engagement with the loop 15; the wind pressure causing the sail to disengage from the latch, and assume a substantially hori-

zontal position parallel with the runner 4. The edge 9 of the sail is the only resistance presented to the wind pressure in the descent, the glider not now having any sustaining power descends the kite line X by gravity, its descent being augmented by the weight 3.

The ascent and descent of the glider as described is an occasion of great joy and entertainment to juvenile kite-fliers, and a fruitful source of instruction in elementary aeronautics. The sail can be given various shapes and contour such for instance as the cross section now generally adopted in aeroplanes which will cause the glider to glide slowly down the string, or ascend or descend rapidly according to individual adjustments that may suggest themselves to the operator.

The glider is particularly advantageous in taking meteorological observations, as various recording instruments can be sent up, at any period during the rise of the kite, the descending glider bringing down the desired information without the necessity and loss of time of reeling in the kite, the observations can also be made at short intervals and at various heights as the kite rises. Other scientific uses will suggest themselves in putting this invention into practice; for instance, an object such as Y, may be suspended on the hook 25 of the

trigger 18, to be released when the trigger bumps into the disk 24 as described.

The area of the sail lends itself to the display of advertising matter; the glider also lends itself to the display of considerable skill in dropping darts such as "Y" on a target resting upon the ground.

While I have shown and described one desirable species embodying this invention, I do not wish to be understood as limiting this invention to the particular form herein shown and described.

Having thus described this invention, what is claimed and desired to secure by Letters Patent is:—

A glider including a runner having spiral guides on the opposite ends thereof; a mast rigidly attached to said runner to form a frame; a sail pivoted on said frame, a latch pivoted on said mast and engaging said sail; a trigger pivoted on said runner adjacent to and projecting beyond the end thereof; a link extending between said latch and said trigger; a tension member adapted to hold said link taut; and means on said trigger for detachably holding an object.

In testimony whereof I have hereunto set my hand this 17th day of July 1914.

CHARLES W. CORNELL, Jr.
